Inventor:

John Traum

UNITED STATES PATENT OFFICE.

JOHN TRAUM, OF COSHOCOTON, OHIO.

COLLAPSIBLE CORE.

1,368,862.

Specification of Letters Patent. Patented Feb. 15, 1921.

Application filed June 30, 1920. Serial No. 393,163.

To all whom it may concern:

Be it known that I, JOHN TRAUM, a citizen of the United States, residing at Coshocton, in the county of Coshocton and State of Ohio, have invented certain new and useful Improvements in Collapsible Cores; and I do hereby declare the following to be a clear and exact description of the invention, such as will enable others skilled in the art 10 to which it appertains to make and use the same.

The invention relates to the construction and vulcanization of casings such as are used in combination with pneumatic tubes. 15 The combination being usually referred to as the pneumatic tire.

The device is a collapsible core upon which the casing is constructed and vulcanized, and the object of the invention is to provide a 20 collapsible core which is made up of a series of sections capable of being quickly and accurately assembled and connected to form an annular core and of being easily and quickly separated and removed, one by one, from the 25 vulcanized casing.

The invention relates particularly to the means by which the adjacent ends of companion sections forming the core may be quickly and easily connected in operative 30 relation, and disconnected in such manner as will allow the separated sections to be removed from the vulcanized casing, and to the adaptability of the parts alining and locking the core sections to any preferred 35 method of constructing the sections, as for example they may be cast hollow, or solid, or they may be employed with pressed metal sections adapted to be mounted on a properly divisioned ring.

40 A very desirable feature of the invention that is not in use in any collapsible core with which I am acquainted, is, that in my invention as described in this specification, there is not required the usual pins and corresponding recesses in the abutting ends of 45 companion sections to aline the assembled core in circumferential relation; the disadvantage of the pins and corresponding recesses which are usually employed, is, that 50 when removing the separated sections from the vulcanized casing, and with the key section removed, the sections remaining within the casing are yet secured in true circumferential alinement at their abutting ends 55 by the pins. Thus, it is evident that one of the ends only of the section to be next

removed is free to move inward and through the rift in the inner periphery of the casing until the angle of its ends relative to the remaining sections is such as will free the 60 union established by the pins with the remaining section.

In my invention as will be readily observed, by the absence of the circumferential alining parts when the sections are to 65 be removed from the vulcanized casing, and, by reason of their lines of division, the sections are peculiarly free to be removed from within the vulcanized casing. With these ends in view the invention consists of the 70 novel construction of parts, and their relative adaptability as hereinafter described, illustrated in the accompanying drawings, and particularly pointed out in the appended claims.

75 Referring to the drawings: Figure 1 is a section of the circumference of the assembled core, illustrating the means employed to aline and lock the sections. Fig. 2 is an end view of one of the sections, a section of 80 the lug adapted to lock the abutting ends of the sections, and is also a cross section of the core. Fig. 3 is a perspective view of one of the slotted, tapered pins adapted to aline the sections. Fig. 4 is a perspective 85 view of a triangular shaped lug that is secured to one end of the abutting ends of companion sections.

Referring to Fig. 1 it will be observed that the angle and points of division of the several sections are such as will allow the separated sections to be removed from the vulcanized casing. To this end it will be noticed that the key section has parallel ends, but it is also desired to direct attention to the 95 fact that the sections adjacent to the key section, separate from the remaining section at substantial right angles to the line of separation from the key section, thereby requiring less effort for their removal from the 100 vulcanized casing than is the case when their lines of division are more nearly true radial lines.

The collapsible core is an annulus which is made up of a plurality of segment shaped 105 sections. Four of the sections are employed in the construction shown, and are indicated in the drawing by reference numbers, 1, 2, 2, and 3. The section 1 is the key section, or the section which must be 110 last placed in position when assembling the core, and is the first section to be removed

when the core is to be removed from the vulcanized casing.

- In the completed form of the invention as described in this specification, the means 5 for separately connecting adjacent sections consists in providing in one of the abutting ends of the sections, tapering openings which receive corresponding tapering pins adapted to be driven in the said openings, 10 having first engaged tapering openings in hereinafter described triangular shaped lugs carried by the companion sections, the said tapering pins simultaneously contacting in keying relation in the alined tapered 15 openings of companion sections, and in cooperation with hereinafter described lugs carried in the outer periphery of one of companion sections securely lock the sections in operative relation.
- 20 Referring to Fig. 1 and to the triangular shaped lugs which are represented by the numerals 4 it will be observed that the lugs are adapted to openings in the ends of the sections, and are permanently secured to the 25 sections by any suitable means, such as by threading the stems 6 or by pins engaging the stems through openings in the sections. The surface of one of the sides of the triangular shaped lugs aline with, and form a 30 continuation of the surface of the ends of the section to which it is secured, and which in the assembled core occupy V shaped openings in the inner periphery of the inwardly directed flange of the sections.
- 35 Tapered openings centrally located in the triangular shaped lugs at substantial right angles to the stem 6 securing the lugs, and coincident with corresponding tapered openings in the adjacent sections, the said tapered 40 openings when alined form acute and obtuse angles with the line of division of companion sections, and are adapted to receive corresponding slotted, tapered pins 5 that aline the abutting ends of companion 45 sections.

Referring to Fig. 3 and to the tapered pins which aline, and in coöperation with the locking device indicated by the numerals 8, and 9, in the drawings, secure the sections, 50 and that are provided with longitudinal slotted openings, 7, the double function of which will be hereafter apparent, it may be remarked that the taper will permit them to readily engage their respective tapered openings when the abutting ends of companion sections are placed in juxtaposition.

Referring to the locking lugs in the outer periphery and at the ends of one of abutting sections, it will be noted that the enlarged 60 triangular shaped ends of the lugs 9, are directed inwardly and are adapted to engage correspondingly directed openings in the abutting ends of their companion sections, and, that by reason of the key sec-

tion having parallel ends it is provided with 65 lug openings in each of its ends adapted to secure lugs carried by the adjacent sections. With the sections exclusive of the key section connected, the union of the key section and the adjacent sections is effected by an 70 outward movement of the key section, or the identical movement given to the key section by the alining action of the tapered pins when they are placed within the nearly alined openings and driven home. 75

By the means described the alining and locking in operative relation of the core sections is brought within the scope of one simple and easily executed operation.

The double function of the longitudinal 80 slotted openings in the tapered pins, is, by the contracting and expanding action given that part of the pin within the triangular shaped lug there is assured a rigid contact between lugs and pins, yet, by the reactive 85 flexibility given that part of the pins by the slotted openings they will be permitted to advance any slight distance within the tapered openings in the lugs that may be required to assure the same rigid contact 90 between the pins and the sections.

A drift of suitable conformation to engage the slots in the pins is the only tool required to disconnect the sections.

With the tapered pins removed from within the tapered openings, the key section, and all the other sections are free to move inwardly and through the rift in the casing.

Having thus described my invention, I declare that what I claim and desire to secure by Letters Patent is:

1. In a collapsible core, the combination of a plurality of sections adapted to abut endwise, inwardly directed flanges carried by the sections, triangular shaped lugs adapted to occupy V shaped openings in the inner periphery and at the contacting points of the flanges carried by abutting sections, the surface of one of their sides alining with and forming a continuation of the surface of the ends of the sections to which the lugs are secured, and means for securing the triangular shaped lugs to the sections. 100

2. In a collapsible core the combination of a plurality of sections adapted to abut endwise, inwardly directed flanges carried by the sections, triangular shaped lugs adapted to and secured to some of the sections, tapered openings in the triangular shaped lugs 110 forming an obtuse angle with the abutting ends of the sections to be alined and locked, the said tapered openings being adapted to receive slotted, tapered pins adapted to engage tapered openings in the abutting ends 120 of adjacent sections coincident with and forming a continuation of the tapered openings in the triangular shaped lugs and at 125

an acute angle with the abutting ends of the sections to be alined and locked.

3. In a collapsible core the combination of a plurality of sections adapted to abut endwise, inwardly directed flanges carried by the sections, lugs adapted to lock the sections in operative relation secured in the outer periphery of one of abutting ends of companion sections, the said lugs being adapted in circumferential direction their ends terminating in inwardly directed projections adapted to engage correspondingly directed openings in the outer periphery of one of abutting ends of companion sections, their union being effected by a radial movement of the sections as substantially described.
4. In a collapsible core the combination of a series of sections adapted to abut endwise, inwardly directed flanges carried by the sections, a key section having parallel ends adapted to secure triangular shaped lugs provided with tapered openings registering with corresponding tapered openings in the adjacent section, slotted tapered pins that 25 aline the sections adapted to be engaged by the said tapered openings in the triangular lugs and in the ends of the abutting sections, circumferential slotted openings in the ends and in the outer periphery of the key 30 section and some of the ends of the series of sections terminating in inwardly directed triangular openings adapted to receive circumferentially directed lugs terminating in inwardly directed projections carried by the 35 sections adjacent to the key section and some of the ends of the series of sections and which with the coöperation of the said slotted tapered pins aline and lock in operative relation the key section and the series of 40 sections forming the annular collapsible core.

In testimony whereof I affix my signature.

JOHN TRAUM.
